[57] CLAIM

The ornamental design of an agricultural tractor, as shown and described.

DESCRIPTION

FIG. 1 is a left side elevational view of an agricultural tractor showing our new design;

FIG. 2 is a right side elevational view thereof;

FIG. 3 is a top plan view thereof;

FIG. 4 is a front elevational view thereof; and

FIG. 5 is a rear elevational view thereof.

The tires shown in broken lines in FIGS. 1-5 are for illustrative purposes only and form no part of the claimed design.
